Application March 25, 1943, Serial No. 480,434

12 Claims. (Cl. 74—286)

This invention relates to drive units for machines whereby various sections of the machine can be driven at different speeds from a single prime mover.

Specifically, the invention relates to a mechanical drive for paper making machines.

The transmission of power from a prime mover to a paper making machine requires installations which provide a means of altering the relative speeds of various sections of the machine to accommodate the variations in expansion and contraction of paper passing through the machine for insuring the necessary "draw" between one section and another, as well as to provide for the speeding up of paper machine rolls which have been reduced in diameter from their original sizes as by regrinding and buffing operations. Heretofore, slight differences in speeds of the various sections of the machine have been accomplished by use of cone pulleys and belt drives from a single line shaft for driving right angle gear units which units drive the inshafts to the machine sections. Such cone pulley and belt drives require appreciable space, involve the use of many bearings, and require wearable belts.

In accordance with this invention the heretofore necessary cone pulleys and belts are entirely eliminated and the units of this invention will not only replace such pulleys and belts, but will also avoid the necessity for additional right angle gear units.

According to this invention a small compact mechanical drive receives the main line shaft therethrough and is positioned at each section of the machine to transmit power from the line shaft to the machine sections at the desired speed and in the desired direction. The units of this invention include a swing gear inshaft drive arrangement accommodating differences in levels of the various inshafts of the machine sections so that direct coupling between the machine section inshafts and the driving shafts of these units is possible even when the inshafts are at different levels at the various sections of the machine.

The units of this invention also include a symmetrical differential drive having one side driven at substantially the same speed as the line shaft, and the other side driven at a slow speed, thereby making possible the use of small and compact parts. This differential drive acts both as a speed reducer and as a power transmitter capable of being readily controlled by a speed changer to deliver power at the desired speed. The differential drive eliminates the necessity for a complicated multi-gear layout.

The units of this invention also include an externally mounted clutch which is readily accessible for inspection and repair. All other power-transmitting parts of the unit are enclosed in a casing.

5 A speed changer is provided in the casing and is adjustable from outside of the casing for regulating the speed of the inshaft driven by the unit relative to the speed of the line shaft driving the unit. The parts are arranged so that only a very small amount of power goes through the speed changer. The speed changer is directly connected through gearing with the line shaft so that it can run at high speed.

10 15 The inshaft driver of the units of this invention can be rotated in either direction by shifting of a single gear in the unit. Thus standard units of this invention are readily adapted for driving all sections of a paper making machine from a single line shaft even though some sections must be driven in the opposite direction relative to other sections.

20 25 It is, then, an object of this invention to provide a compact, efficient mechanical drive unit adapted for paper making machinery.

A further object of the invention is to provide a mechanical drive adapted to deliver power efficiently from a prime mover at a selected level and in a selected direction.

30 35 A further object of the invention is to provide a clutch-controlled mechanical drive unit adapted to receive a line shaft therethrough and including a speed changer device and a power delivery arrangement enclosed in a casing separate from the clutch.

A still further object of the invention is to provide a variable speed mechanical drive unit for paper making machines wherein about ninety percent of the power is directly transmitted 40 to the power delivery end thereof while about ten percent of the power passes through a manually adjustable speed changer and is added to the direct power.

45 A still further object of the invention is to provide a mechanical drive adapted for paper making machines including a speed changer which receives therethrough only from eight to ten percent of the power input to the unit.

A further object of the invention is to provide 50 a paper machine mechanical drive unit including a simplified differential drive acting both as a speed reducer and a controlled speed transmitter.

A further object of the invention is to provide 55 a differential drive unit having one side thereof driven at the speed of a prime mover and the

other side thereof driven at a selected slow speed to control the power delivery speed of the unit.

A still further object of the invention is to provide a paper machine sectional drive unit having a swingable gear casing adapted to be positioned at a desired level for direct coupling of the delivery shaft of the unit with an inshaft of the paper machine.

Other and further objects of the invention will be apparent to those skilled in the art from the following detailed description of the annexed sheets of drawings which, by way of preferred example only, illustrate one embodiment of the invention.

On the drawings:

Figure 1 is a perspective view of a sectional drive unit of this invention.

Figure 2 is a longitudinal vertical cross-sectional view, with parts in elevation, of the drive unit of this invention.

Figure 3 is a horizontal cross-sectional view, with parts in top plan, taken along the line III-III of Figure 2.

Figure 4 is a vertical cross-sectional view, with parts in elevation, taken along the line IV-IV of Figure 3.

Figure 5 is a fragmentary side-elevational view taken along the line V-V of Figure 4.

Figure 6 is a vertical cross-sectional view, with parts in elevation, of the speed changer taken along the line VI-VI of Figure 4.

As shown on the drawings:

In Figures 1 to 5 inclusive the reference numeral 10 designates generally a sectional drive or mechanical drive unit according to this invention. The unit 10 has a main base frame 11 with a mounting flange therearound as best shown in Figure 1 for securing the unit on the floor, for example, on the rear side of a paper making machine. The frame 11 includes an upstanding pedestal 12 at one end thereof carrying a bearing housing 13. A box or casing 14 is formed integral with the base on the end thereof remote from the pedestal 12. This box 14 has a removable side plate 15 covering an opening in a side wall thereof. The box has an open top closed by a dome-like cover 16 which cover in turn has a removable inspection plate 17 on the top thereof.

As best shown in Figure 2 the box 14 has a vertical partition wall 18 therein with apertures 19 and 20 therethrough. The end wall of the box 14 adjacent the pedestal 12 has apertures 20 and 21 therethrough. The other end wall of the box remote from the pedestal 12 has apertures 22 and 23 therethrough. As shown in Figure 3, the front and rear side walls of the box 14 have aligned apertures 24 and 25 therethrough.

A main line shaft 26 extends longitudinally through the entire unit 10 and is rotatably mounted in a bearing 27 carried by the bearing housing 13 on the pedestal 12 and in a bearing provided in a bearing housing 28 secured on the outside of the box 14 around the aperture 22 as best shown in Figure 2.

A hollow shaft 29 is freely disposed around the main shaft 26 and is rotatably supported in the unit 10 on a bearing 30 carried in the aperture 20 and in a second bearing 31 carried in the aperture 22. The hollow shaft 29 is thus rotatably mounted in the unit 10 and extends from the bearing 31 through and beyond the bearing 30 to terminate in the space between the box and the pedestal 12.

A clutch 32 has the driving part 33 thereof keyed to the line shaft 26 together with a driven

part 34 keyed to the hollow shaft 29. The clutch 32 includes a series of friction disks 35 slidably splined to the driving part 33 alternating with a series of shoes 36 slidably splined to the driven part 34. The shoes 36 can be urged into friction engagement with the disks 35 to couple the parts 33 and 34 of the clutch, thereby driving the hollow shaft 29 from the line shaft 26.

The hollow shaft 29 passes freely through the aperture 19 in the partition wall 18.

As also shown in Figure 2, a differential unit shaft 37 is rotatably supported in the box 14 on a bearing 38 carried in a housing mounted in the aperture 20 of the partition wall 18 and

15 in a bearing provided in a housing 39 mounted in the aperture 23. A differential spider 40 is keyed to the shaft 37 between the bearing supports for the shaft and has bevel gears 41 rotatably mounted around the end portions thereof on bearings 42. A hollow shaft 43 is rotatably mounted on bearings 44 around the shaft 37 and has a beveled gear 45 on an end thereof meshing with the gears 41. A second hollow shaft 46 is rotatably mounted around the shaft 37 on bearings 47 and has a bevel gear 48 on the end thereof also meshing with the bevel gears 41.

A gear 49 secured on the hollow shaft 29 meshes with a similar sized gear 50 secured on the shaft 43. The shaft 43 is thus driven from the shaft 30 29 at the same speed as the shaft 29.

A gear 51 is secured on the hollow shaft 46 of the differential unit for a purpose to be hereinafter described.

A bevel gear 52 is keyed on the end of the shaft 37 which projects beyond the partition plate 18.

The bevel gear 52 meshes with a mating bevel gear 53 on a transverse shaft 54 best shown in Figure 3. This shaft 54 has one end thereof 40 rotatably carried in a bearing 55, which bearing 55 is mounted in a housing carried in the aperture 24.

A gear casing 56 has a hollow circular neck portion 57 projecting into the opposed aperture 25 and carrying a bearing 58 for rotatably supporting an intermediate portion of the shaft 54. The shaft 54 projects into the gear casing 56 and carries a spur gear 59 on the end portion thereof meshing with a large gear 60 on the power delivery shaft 61 of the unit. This shaft 61 is rotatably mounted on bearings 62 carried in the casing 56.

As shown in Figures 3, 4 and 5, the back face of the casing 56 has an arcuate pad 63 thereon while the front face of the box 14 and cover 16 have laterally projecting lugs 64 extending into contact with this pad 63. These lugs 64 are internally tapped. The casing 56 is swung in the aperture 25 to position the power delivery shaft 61 at the desired level and holes are then drilled through the back face of the casing in alignment with the tapped lugs 64. Bolts 65 are then inserted through the holes and threaded into the top lugs 64 for holding the casing at the desired level. This arrangement makes possible the uniform production of drive units which can be readily arranged so that their delivery shafts will be at the proper levels to meet the particular installation requirements.

70 As shown in Figure 2, a gear 66 is secured on the hollow shaft 29 adjacent the gear 49, and as shown in Figures 3 and 4, drives a larger gear 67 secured on the drive shaft 68 of a speed changer unit designated generally by the reference numeral 69.

The speed changer unit 69, as best shown in Figure 6, is mounted in a casing 70 which rotatably carries the shaft 68 together with a second shaft 71 spaced from the shaft 68.

A pair of bevel faced wheel flanges 72 are slidably keyed on the shaft 68 while a second pair of bevel faced wheel flanges 73 are slidably keyed on the shaft 71. The bevel-faced wheel flanges cooperate to provide a V-pulley. A V-belt or other driver band 74 is trained around the resulting V-pulleys to drive the shaft 71 from the shaft 68.

Link arms 75 are pivotally supported intermediate their ends in the casing 70 and are pivoted to the aligned wheel flanges 72 and 73 of each pair. The pivot point for the link arms 75 is between each wheel flange.

The free ends of the lever 75 are pivoted to bosses 76 which are threaded onto a control rod 77 having right and left hand threaded portions 78 and 79 respectively receiving the bosses 76 thereon. A hand wheel 80 is secured on the rod 77 on the outside of the main casing box 14 as shown in Figure 3 so that the speed changer can be adjusted from outside of the unit 10. Rotation of the hand wheel 80 in one direction will draw the beveled wheel flanges 73 toward each other while separating the wheel flanges 72 thereby causing the band 74 to ride further inwardly from the periphery of the wheel flanges 72 than from the peripheries of the wheel flanges 73. As a result, the shaft 71 will be rotated at a slower speed than the shaft 68. In this manner the speed of the shaft 71 can be regulated relative to the speed of the shaft 68.

The shaft 71 drives a gear 81 meshed with a gear 82 on a stub shaft 83 as best shown in Figures 3 and 4. This stub shaft 83 is rotatably supported in a bearing 84 carried by the partition wall 18 of the box 14. A gear 85 is also secured on the stub shaft 83 and meshes with the gear 51 on the hollow differential shaft 46.

As shown in Figures 2 and 3, the aperture 21 in the box 14 does not support a bearing and is merely closed with a cover plate 21a. This cover plate 21a can be removed for inspection of the position of the bevel gears 52 and 53. As shown in Figure 3, the bevel gear 53 can be switched from the position shown in solid lines to the position shown in dotted lines for reversing the rotation of the power delivery shaft 61. Thus, changing the position of only one gear 53 reverses the direction of rotation of the power delivery shaft of the unit of this invention and makes possible the production of standardized units for all installations.

In operation, power from a prime mover (not shown) drives the line shaft 26. When the clutch 32 is actuated so as to couple the driving and driven parts 33 and 34 thereof, the hollow shaft 29 is driven at the same speed as the line shaft 26. This shaft 29 will drive the gear 45 of the differential unit 37 through the gears 49 and 50, and the shaft 43. The differential unit is symmetrical so that the gear ratio through the differential between gears 50 and 51 is the same. Since the gears 49 and 50 are of the same size, a 1-to-1 gear ratio exists between shaft 29 and shaft 43 of the differential unit. One side of the differential unit is thus driven at the same speed as the prime mover, viz., shafts 26 and 29.

The other side, viz., shaft 46, of the differential unit is driven by gear 51. This gear 51 is driven at a selected slow speed through a double reduction of gears (gears 85, 82, and 81) by the speed

changer 69. The arrangement is such that if shaft 46 were held stationary by gear 51, and gear 50 drove shaft 43 at, say, 1000 revolutions per minute, differential unit shaft 37 would be driven at 500 revolutions per minute, or half the speed of shaft 43. Now, since gear 51 is always driven slowly relative to gear 50, the differential unit acts as a speed reducer without the necessity for a heavy worm and wheel drive or other strong gear reduction drives capable of transmitting heavy loads. The arrangement cuts down the number of gears and heavy working parts heretofore required in speed reducers.

In addition to its function as a speed reducer, the differential unit serves the dual function of accommodating differences in speed so that the power delivery shaft 61 may be driven at a selected speed relative to the speed of the line shaft 26 as determined by the speed changer 69.

20 The speed changer 69 is driven by the shaft 29 through the gears 66 and 67. This speed changer is then regulated by a manipulation of the hand wheel 80 to drive the shaft 71 thereof at a desired speed and this shaft 71 will drive 25 the differential shaft 46 at a slow speed through the double reduction gears 81, 82, 85, and 51. The slow driven differential shaft 46 actuates the differential gears 41 and the shaft 37 is driven at a reduced speed relative to shaft 29 determined 30 by the speed changer 69. The shaft 37, in turn, drives the power delivery shaft 61 through the bevel gears 52 and 53, shaft 54, gear 59, and gear 60.

Therefore, the power delivery shaft 61 can be 35 driven at any desired speed relative to the speed of the line shaft 26 by manipulation of the hand wheel 80 for setting the speed changer.

Now, since the differential unit is symmetrical, the twisting effort on gears 50 and 51 to turn 40 shaft 37 against a load is the same. Therefore, the relative amount of power put into the differential unit through gears 50 and 51 is directly proportional to the speeds at which these gears are driven according to the formula:

$$45 \text{ Torque (twisting effort in ft. lbs.)} = \frac{5250 \times \text{horsepower}}{\text{Revolutions per minute}}$$

50 As explained above, gear 50 is driven at the same speed as the line shaft 26, but gear 51 is 55 back geared down to the speed changer 69, through a double reduction of gears so that it is driven very slowly. Because of this arrangement, only about 10% of the power input to shaft 37 comes through the speed changer 69 while about 90% of the power input to shaft 37 comes direct from the line shaft 26 and hollow shaft 29. As a result, the differential unit can be small and compact.

60 The clutch 32 connecting the hollow shaft 29 with the line shaft 26 can be of any suitable construction, but a compressed air-operated multiple disk clutch is preferred since such a clutch can be controlled from a remote point.

65 In installing the units of this invention on a paper making machine one unit is mounted at the rear side of the machine adjacent each in-shaft to the machine. The line shaft then passes through all of the units and the units are selectively operated through their clutches 32 at adjustable speeds determined by manipulation of their hand wheels 80. If any unit must rotate an in-shaft of the paper machine in a direction 70 opposite to other units, such reverse rotation can

be obtained by changing the position of the gear 53 as shown in Figure 3.

It will, of course, be understood that various details of construction may be varied through a wide range without departing from the principles of this invention and it is, therefore, not the purpose to limit the patent granted hereon otherwise than necessitated by the scope of the appended claims.

I claim as my invention:

1. A mechanical drive comprising a hollow drive shaft adapted to receive a line shaft therethrough, a clutch adapted to selectively connect the drive shaft with a line shaft received therethrough, a differential unit having one side thereof driven by said hollow shaft, a speed changer driving the other side of said differential unit, means driving said speed changer from said hollow shaft, a differential shaft driven by said differential unit, a transverse shaft driven by said differential unit shaft, a gear casing swingable about said transverse shaft, a power delivery shaft rotatably mounted in said gear casing, gears in said casing connecting said transverse shaft with said power delivery shaft, said power delivery shaft adapted to be positioned at a desired level by swinging said gear casing about said transverse shaft, and said speed changer unit adapted to be adjusted for controlling the speed of said power delivery shaft relative to the speed of said hollow drive shaft.

2. A mechanical drive comprising a drive shaft, a symmetrical differential unit having opposed driven sides, a speed changer driven by said drive shaft, means driving one side of said differential unit from said drive shaft at substantially the same speed as the drive shaft, means driving the other side of said differential unit from said speed changer at a slow speed relative to the drive shaft and relative to the speed changer drive, a power transmission shaft driven by said differential unit at a speed determined by the speed changer, said means driving one side of the differential unit from the drive shaft transmitting about 90% of the power from the drive shaft to the power transmission shaft, and said speed changer driven by the drive shaft together with said means driving the other side of the differential from the speed changer transferring about 10% of the power of the drive shaft to said power transmission shaft.

3. A mechanical drive unit comprising a frame adapted to be mounted on a floor adjacent a machine and receive a line shaft therethrough, a hollow drive shaft rotatably carried by said frame around said line shaft, a clutch having a driving part keyed to said line shaft and a driven part keyed to said hollow drive shaft for selectively connecting the line shaft and hollow drive shaft, a differential shaft rotatably mounted on said frame in spaced parallel relation from said drive shaft, a spider secured on said differential shaft, beveled gears rotatably mounted in spaced opposed relation around said spider, a first beveled gear unit rotatably mounted around said differential shaft in meshed engagement with the spider carried beveled gears, a second beveled gear unit rotatably mounted around said differential shaft on the opposite side of said spider in meshed engagement with said spider carried beveled gears, gears connecting said first beveled gear unit with the said drive shaft for driving said first unit from said drive shaft, a speed changer unit mounted on said frame having a drive shaft and a driven shaft with means therebetween controlling the speed of the driven shaft

relative to the drive shaft, means connecting said hollow drive shaft with the drive shaft of the speed changer, means connecting the driven part of the speed changer with the second beveled gear unit, a beveled gear secured on said differential shaft, a power transfer shaft at right angles to said differential shaft, a beveled gear on said power transfer shaft driven by said beveled gear on the differential shaft, a casing 5 swingably mounted on said frame for rotation about said power transfer shaft, a power delivery shaft rotatably mounted in said casing, a gear on said power transfer shaft in said casing, and a gear on said power delivery shaft in said casing meshing with said gear on the power transfer shaft.

4. A machine sectional drive unit which comprises a frame having an upstanding pedestal at one end thereof and a closed box at the other 20 end thereof in spaced relation from said pedestal, a bearing carried by said pedestal, an aligned bearing carried by said box, a main drive shaft projecting through said box and rotatably supported in said bearings, a hollow drive shaft surrounding said line shaft in said box and projecting into spaced relation from said pedestal, bearings carried by said box rotatably supporting said hollow drive shaft, a clutch between said pedestal and said box having a driving part 25 connected to said line shaft and a driven part connected to said hollow drive shaft for selectively driving the hollow drive shaft from the line shaft, a differential shaft rotatably mounted in said box, a differential unit having opposed 30 gears rotatably mounted on said differential shaft, a spider secured on said differential shaft, gears rotatably carried by said spider meshing with said opposed gears, a power transfer shaft rotatably mounted in said box at right angles to said differential shaft, said power transfer shaft projecting to the outside of said box, connecting gears joining the differential shaft and the power transfer shaft for co-rotation, one of said connecting gears being shiftable on its shaft to drive 35 the power transfer shaft from the differential shaft in either direction, a gear casing swingably mounted on the outside of said box receiving the projecting end of the power transfer shaft therein, a power delivery shaft rotatably mounted in 40 said gear casing, means for securing said gear casing to said box at a selected level, gears in said casing connecting said power transfer shaft and said power delivery shaft for co-rotation, a speed changer unit in said box driven by said hollow drive shaft and driving one opposed gear 45 of the differential unit, and gears directly connecting said hollow drive shaft with the other opposed gear of the differential unit whereby said differential shaft will be driven at a speed relative to the hollow drive shaft controlled by the power transfer shaft.

5. A mechanical drive unit comprising a main frame defining a hollow box, a hollow drive shaft extending through said box and rotatably carried thereby, said drive shaft adapted to receive a line shaft therethrough, a clutch for driving the hollow drive shaft from an inserted line shaft, a differential shaft rotatably mounted in said box in spaced parallel relation to said hollow drive shaft, first and second differential gears members rotatably mounted around said differential shaft, a spider secured to said differential shaft, gears rotatably carried by said spider meshing with said first and second differential gear members, a gear secured on said hollow drive shaft in

said box, a similar sized gear secured on said first differential gear member meshing with said hollow drive shaft gear, a speed changer unit in said box, means connecting opposite sides of said speed changer unit with said hollow drive shaft and said second differential gear unit for passing only a small amount of power from the drive shaft through the speed changer, means projecting to the outside of said box for adjusting said speed changer, a power transfer shaft rotatably mounted in said box at right angles to said differential shaft and having an end projecting to the outside of said box, a beveled gear secured on said differential shaft, a second beveled gear secured on said power transfer shaft meshing with said beveled gear on the differential shaft, said second beveled gear adapted to be positioned on opposite sides of the differential shaft carried beveled gear to drive the power transfer shaft in opposite directions, a gear outside of said box on the projecting end of said power transfer shaft, a second gear outside of said box meshing with the power transfer shaft carried gear, and a power delivery shaft driven by said second gear, said second gear being rotatable about the power transfer shaft carried gear to position the power delivery shaft at a desired level.

6. Apparatus adapted for driving a section of a paper machine from a line shaft at a predetermined speed relative to the speed of the line shaft which comprises, a main frame adapted to receive a line shaft therethrough, power transfer means mounted on said main frame adapted to be driven by said line shaft, said power transfer means including a differential unit, a differential shaft, and a speed changer controlling the speed of the differential shaft, a power delivery shaft driven from said differential shaft adapted to be coupled with a section of a paper machine, a bearing support for the power delivery shaft, a pivot for said bearing support spaced radially therefrom, a pivot support on the main frame swingably carrying the bearing support, and means for selectively securing the bearing support to the main frame for positioning the power delivery shaft at a desired level whereby the line shaft need not be changed to drive inshafts to the paper machine located at different levels.

7. A mechanical drive unit comprising a drive shaft, a differential unit having first and second driven sides and an intermediate driving part, a speed changer, a power delivery shaft driven by said differential unit, gears driven by the drive shaft arranged to drive the first side of the differential unit at the same speed as the drive shaft, and reduction gears connecting the speed changer with the second side of the differential unit for driving said second side of the differential unit at a much slower speed than the drive shaft and the speed changer, said gears driving the first side of the differential unit transmitting about 90% of the power from the drive shaft, and said reduction gears driving the second side of the differential unit transmitting about 10% of the power from the drive shaft, whereby the speed changer is not subjected to heavy loads.

8. Apparatus adapted for driving a machine section at a controlled speed slower than the speed of a prime mover which comprises a prime mover driven main drive shaft, a differential unit having first and second driven sides, gears drivably connecting the first side with the main drive shaft to drive the first side at substantially the

same speed as the main drive shaft, a speed changer unit having a drive shaft geared to the main drive shaft to rotate at a slightly slower speed than the main drive shaft, said speed changer unit having a driven shaft selectively driven from the drive shaft thereof at a selected decreased speed relative thereto, reduction gears drivably connecting the driven shaft of the speed changer unit with the second side of the differential unit and arranged to rotate said second side of the differential unit at a controlled speed materially less than the speed of said speed changer driven shaft, a differential shaft driven by said differential unit at a speed controlled by said speed changer, a power transfer shaft driven by said differential shaft, and a power delivery shaft driven by said power transfer shaft and arranged to swing relative to the power transfer shaft for changing the level thereof.

9. A mechanical drive comprising a driver, a differential having first and second driven sides and a driving shaft, a speed changer, gears connecting the driver with the first side of the differential arranged to transmit most of the driving torque from the driver to said first side of the differential, reduction gears connecting the driver with the speed changer to drive the speed changer at slower speeds than the driver, additional reduction gears connecting the speed changer with the second side of the differential to drive said second side at a materially lower speed than the speed of the driver and the speed of the speed changer, and a power delivery shaft driven by said driving shaft of the differential, whereby most of the driving torque from the driver is transmitted to the delivery shaft through the differential and gears connecting the driver with the first side of the differential while said speed changer transmits only a small amount of the driving torque but controls the ultimate speed of the power delivery shaft.

10. A machine section drive comprising a main frame, aligned bearings carried by said main frame at a fixed level, a driver rotatably supported on said frame in said bearings, a secondary frame swingable on said main frame about a pivot, a power delivery shaft rotatably carried by said secondary frame to rotate about an axis radially offset from the pivot, means for selectively fixedly connecting the main and secondary frames to position the power delivery shaft at a desired level, said driver and power delivery shaft being at right angles to each other, and means carried by said main and secondary frames for transmitting power from the driver to the power delivery shaft irrespective of the selected level for the power delivery shaft.

11. A mechanical drive comprising a driver, a differential having first and second driven sides and a driving shaft, a speed changer, means connecting the driver with the first side of the differential arranged to transmit most of the driving torque from the driver to said first side of the differential, reduction means connecting the driver with the speed changer to drive the speed changer at slower speeds than the driver, additional reduction means connecting the speed changer with the second side of the differential to drive said second side at a materially lower speed than the speed of the driver and the speed of the speed changer, and a power delivery shaft driven by said driving shaft of the differential, whereby most of the driving torque from the driver is transmitted to the delivery shaft through the differential and said means connecting the driv-

er with the first side of the differential while said speed changer transmits only a small amount of the driving torque but controls the ultimate speed of the power delivery shaft.

12. A machine section drive as claimed in claim 11 further comprising a main frame, aligned bearings carried by said main frame at a fixed level, a driver rotatably supported on said frame in said bearings, a secondary frame swingable on said main frame about a pivot, a power delivery ⁵ 10

shaft rotatably carried by said secondary frame to rotate about an axis radially offset from the pivot, means for selectively fixedly connecting the main and secondary frames to position the power delivery shaft at a desired level, and means carried by said main and secondary frames for transmitting power from the driver to the power delivery shaft irrespective of the selected level for the power delivery shaft.

LLOYD HORNBOSTEL.
